LATCH

Lloyd L. Anderson, Grand Rapids, Mich., assignor
to Winters & Crampton Corporation, Grand-
ville, Mich., a corporation of Michigan

Application October 18, 1937, Serial No. 169,633

8 Claims. (CL. 292—64)

This invention relates to latches designed particularly for use with refrigerators and adapted to be mounted and housed within a refrigerator door. It is of course to be understood that the 5 latch is adapted for use on other doors than refrigerators and is not applicable only to refrigerators.

It is an object and purpose of the present invention to produce a practical, serviceable, and 10 economically manufactured latch which, when applied to a door and the latch bolt engaged with a keeper on a cooperating door frame or jamb, securely holds the door in closed position. A further object of the invention is to provide a 15 latch in which the latch bolt is one member of a toggle structure, the bolt having a hinged connection to the other member thereof at the knee or knuckle of the toggle, and to releasably hold the knee or knuckle of the toggle against breaking whereby the latch bolt, so long as the holding 20 or toggle breaking stopping means is in position, will securely engage with the keeper to hold the door closed. However, through any suitable manually operable means for releasing said toggle holding means, the toggle may be permitted to break and the latch bolt disengage from the keeper for opening the door. Further, in closing the door the bolt is provided with yielding spring 25 means whereby it may move bodily inward with respect to the door on which it is mounted so as to pass over a cam on the keeper and then, under the action of the spring, project into the recess of the keeper.

An understanding of the invention may be had 30 from the following description, reference being made to the accompanying drawings, in which:

Fig. 1 is a fragmentary horizontal section through the free vertical edge portion of a door and the adjacent refrigerator casing on which 40 the keeper is mounted, the latch being shown in plan and with the bolt engaged with the keeper.

Fig. 2 is a vertical section substantially on the plane of line 2—2 of Fig. 1, looking in the direction indicated by the arrows.

Fig. 3 is a horizontal section through the latch 45 between its opposed sides.

Fig. 4 is a similar section showing the latch bolt retracted, and

Fig. 5 is a section substantially on the plane 50 of line 5—5 of Fig. 3, looking in the direction indicated.

Like reference characters refer to like parts in the different figures of the drawings.

In the construction of the latch, a supporting 55 housing is provided, made from flat metal pressed

into U-shaped form, having a connecting web 1 at the inner side with spaced apart parallel sides 2 extending therefrom. Each of said sides at its outer free edge portion is turned at right angles, making attaching flanges 3 which, as shown 5 in Fig. 1, bear against a part of the refrigerator door A when the latch is housed therein, screws passing through the attaching flanges for securing the latch permanently in place. A bolt guide in the form of a U-shaped stirrup is provided, 10 having sides 4 connected by a cross member 5. This guide is located between the sides 2 of the supporting housing, as shown in Figs. 3 and 4, said sides 4 having a permanent connection by spot welding or otherwise, to the sides 2 of the 15 housing.

The latch bolt comprises a keeper engaging head 6 made preferably from Bakelite, though any suitable material may be used. Flat bars 7 at their outer ends are set into the sides of the head 6 and permanently secured thereto. Said bars extend inwardly from the bolt in spaced apart relation and at their inner end portions have longitudinal slots 8 cut therein through which a pin 9 passes, such pin forming the pivot 25 at the knee or knuckle of the toggle structure to which reference has been made.

The toggle structure is completed by a member which is formed from flat metal with two spaced apart arms 10 connected adjacent one 30 end by cross bar 11 integral therewith. The arms 10 come within the inner sides of the arm 1 and the pin 9 passes through the outer end portions of said arms 10 while a second pin 12 mounted on and extending between the sides 2 of 35 the supporting member of the latch passes through the inner end portions of said arms 10. This construction provides a toggle, the arms 10 being adapted to turn about the axis of the pin 12 whereupon the latch bolt is retracted and its 40 inner end portion turned inwardly as shown in Fig. 4.

A member 13 of flat metal is mounted on the pin 9 substantially midway between its ends and extends toward the bolt head 6 from which a 45 projection 14 extends toward the member 13. A coiled compression spring 15 has its end portions passing over the member 13 and the projection 14, the effect of the spring being to normally move the bolt to outer position. However, when 50 a suitable force is applied against the bolt head 6 the bolt consisting of said head 6 and the bars 7, may be moved bodily inward for a distance which is controlled by the length of the slots 8.

A pin 16 is located between the sides 2 of the 55

support and carried thereon in front of the pivot pin 9 of the knee or knuckle of the toggle when the bolt is in its operative latching position as shown in Figs. 1 and 3. On the pin 16 a toggle holding or stop member is pivotally mounted, formed from a single piece of flat metal with spaced apart sides 17 connected at their outer ends by an integral cross member 18. The sides 17 are provided with curved slots 19 as shown through which the ends of the pin 9 extend. The sides 17 are located against the outer sides of the bars 1 as shown in Fig. 5.

With the latch in its operative latching position, as shown in Figs. 1 and 3, the pin 9 is in the upper ends of the curved slots 19 which curve away from the pin toward the direction of the free edge of the door in which the latch is mounted so that the pin has a bearing against the lower sides of the upper end portions of the slots. A coiled torsion spring 20 surrounds the pin 16 and has one arm at an end thereof resting against the inner side of the connecting bar 18 and the other arm 22 against a lip 23 which is struck from an adjacent side 2 of the latch housing or support. The tendency of the spring is to rotate the stop or holding member consisting of the parts 17 and 18 in a counterclockwise direction or to the position shown in Figs. 1 and 3. In such position the toggle lever is securely held against breaking at the knee or knuckle because of an impossibility of the pin 9 moving toward the front of the door, being stopped against such movement by the parts of the sides 17 which extend under the pin 9 toward the slots 19.

The sides 17 of said holding member are provided with laterally extending arms 24 at their outer end portions and to one side thereof, through which arms a pin 25 extends. A fork 26 has the two branches thereof connected to the opposite ends of the pin 25 outside of the arms 24. A pin 27 is connected to the fork at its middle portion and extends outwardly and passes through the front side of the door A as shown in Figs. 1 and 2. A vertically positioned handle 28, having a central web 29, is secured to the door, the pin 27 extending into a recess in said web and being surrounded within said recess by a compression spring 30. A manually operable push bar 31 is mounted on the handle, the handle being vertically slotted for projection of the narrower portion of the handle through said slot. The inner part of the handle has laterally extending ribs 32 against which the spring 30 engages at one end to normally hold the push bar 31 in its outer position, the handle being stopped at its outer position by engagement of the ribs 32 against the bottom of the recess within the web 29 of the handle. Pushing inward on the operating push bar 31 compresses the spring 30 and moves the pin or rod 27 inwardly, thereby turning the toggle holding stop member in a clockwise direction. Such turning movement not only frees the pin 9 of the stop which has held it, but at the same time the curved outer sides of the slots 19 act as cams against said pin 9 to move it away from the web 1, thereby not only breaking the toggle, but moving the toggle consisting of the latch bolt and the arms 10 toward the position shown in Fig. 4.

The means shown and described for releasing and breaking the toggle structure is one only of a great many that can be used; therefore the invention is not to be limited in any respect to the specific manually operable toggle releasing means shown and specifically described.

On the front door frame of the refrigerator B a suitable keeper 33 of conventional design is secured, having a recess to receive the head 6 of the latch bolt in front of which is a cam for the rear cam side of the bolt to ride over in closing the door. The spring 20, with the door in open position, and the push bar 31 released, will move the parts of the latch to the position shown in Figs. 1 and 3. When the door is closed the cam inner or rear side of the bolt 6 rides over the cam portion of the keeper 33, moving the bolt longitudinally inward and compressing spring 15 until the bolt has passed beyond the cam on the keeper whereupon the bolt is projected into the recess of the keeper by the spring 15.

As is common in refrigerator constructions, a cushioning compressible gasket 34, usually of rubber, is secured at the rear side of a projecting lip or riser 35 at the free edges of the refrigerator door. This gasket is compressed when the door is closed and the latch has engaged with the keeper, and provides a very secure seal to the door, preventing escape of refrigerated air or the entrance of warmer air from the outside.

In releasing the latch from the door it is necessary merely to clasp the handle 28 and with the palm of the hand push inwardly on the push bar 31. This moves the holding member for the toggle latch structure to release the pin 9 at the knee or knuckle of the toggle and move the same outwardly for a distance. As soon as the toggle is broken the force of the compressed gasket 34 acts to move the door outward and away from the side of the refrigerator to which it has been latched, and acts to turn the parts of the latch still farther in the direction toward which they were started by operation of the push bar 31, or eventually to the position shown in Fig. 4 in which the latch bolt is free of the keeper and the door may be readily opened. Then, as soon as the push bar 31 is released, the door being open, the latch parts assume the position such as shown in Figs. 1 and 3. The door closing operation consists in swinging the door to closed position with the head 6 of the latch bolt riding on the cam of the keeper until it reaches the keeper recess and thereupon it is projected into said recess by the spring 15.

The structure described is relatively simple, economically manufactured, durable and sure in its service and operation.

The invention is defined in the appended claims and is to be considered comprehensive of all forms of structure coming within their scope.

I claim:

1. In a latch structure, a support having spaced apart sides, a latch bolt located between the sides of the support, a guide carried by said support for the latch bolt, a member pivotally mounted at one end between the sides of the support and having a direct pivotal connection at its opposite end to the inner end of the latch bolt, thereby providing a toggle structure, stop means mounted on said support having a connection with said toggle structure at its breaking point, whereby movement of said stop means will cause a pivotal movement of said toggle structure.

2. In a latch structure, a supporting housing, a member pivotally mounted at one end near one end of the housing and within the same, a latch bolt adapted to be located in alignment with said member, a guide for the outer end of the latch bolt, a pivot pin directly connecting said member and latch bolt whereby when said member is pivotally turned in one direction the latch bolt is

- carried inwardly and simultaneously tilted, and a releasable holding means connected with said pivot pin and serving as a stop therefor, to hold it against movement and thereby prevent pivotal movement of said member, combined with means for manually moving said holding means thereby causing a pivotal movement of said pivot pin, as specified.
3. A latch structure comprising, a U-shaped support having spaced apart sides connected by a web extending between said sides at one edge thereof, a guide secured to and lying between the sides of the support, a latch bolt including a head and bars extending therefrom mounted for movement in the guide, a member pivotally mounted on and between the sides of the support and adapted to be located in alinement with said latch bolt, a pivot pin extending through the inner end of said member and through the latch bolt bars, a second member movably mounted on and between the sides of said support extending toward and around said pivot pin and serving as a stop therefor to hold the pivot pin and associated parts against movement away from said web, and manually operable means for moving said holding member to thereby move said pivot pin and cause a movement thereof and of the parts associated and connected therewith away from said web, as and for the purposes specified.
4. In a latch structure, a support, a latch bolt, a member pivotally connected directly to the inner end of the latch bolt, said member being pivotally connected to the support at its opposite end thereby providing a toggle structure having a breaking point at the inner end of the latch bolt, movable means mounted on said support adapted to engage with said toggle structure at said breaking point to hold the joint between the latch bolt and said member against breaking and thereby hold said mentioned member of the toggle structure against pivotal movement, and manually operable means for moving said holding member to thereby positively break the toggle structure, as specified.
5. In a latch structure, a support of U-shape, having spaced apart sides and a connecting web joining said sides at one of their longitudinal edges, a member pivotally mounted at one end adjacent said web and adjacent one end of and between the sides of said support, said member being adapted to extend in parallel relation to and closely adjacent said web, a latch bolt pivotally connected directly to the opposite end of said member and adapted to lie substantially parallel to and closely adjacent said web, a guide for the outer end of the latch bolt carried by the support, a second member pivotally mounted on and between the sides of said support at a distance away from the web, the axis of its pivotal mounting and the axis of the pivotal connection of said latch bolt and first member lying in a plane located substantially at right angles to the plane of said web, said second member being adapted to engage with the pivotal connection of the latch bolt and said first member to hold said latch bolt and connected member against movement away from said web, and manually operable means for moving said second member to thereby force a pivotal movement of said latch bolt and connected first mentioned member, as and for the purposes specified.
6. A construction containing the elements in combination defined in claim 5, combined with yielding spring means for returning said holding member to its initial holding position when free to do so.
7. In a latch structure, a support having spaced apart sides connected at one longitudinal edge by a web, a bolt guide between said sides of the support at one end thereof and spaced from said web whereby the web forms a part of the guide, a member pivotally mounted at one end between the sides of the support and adjacent the opposite end of said support, a latch bolt guided at its outer end in said guide and having pivotal connection at its inner end to the other end of said member, said latch bolt and member normally lying in alinement and substantially parallel to the web, and means movably mounted on said support between the sides thereof at a distance away from the web and extending around said pivotal connection acting to hold said latch bolt and member to which it is pivotally connected from movement, combined with manually operable means for moving said last mentioned means to thereby force a movement of said pivotal connection whereby the latch bolt is positively retracted, substantially as described.
8. In a latch structure, a support of U-shape having spaced apart sides and a connecting web between said sides at one of their longitudinal edges, a member pivotally mounted at one end adjacent said web and adjacent one end of and between the sides of said support, said member normally being adapted to extend in substantially parallel relation to and closely adjacent said web, a latch bolt comprising, an outer head and bars attached one to each side thereof extending inwardly therefrom and normally adapted to lie substantially parallel to and closely adjacent said web, said bars at their inner end portion being longitudinally slotted, said bars and the inner end of said member overlapping each other, a pivot pin extending through the slots in said bars and through the adjacent end of said member, a coiled compression spring between the head of the bolt and said pivot pin, a guide for the head of said bolt located between the sides of said support and spaced from said web whereby the web forms a part of said guide, a second member pivotally mounted on and between the sides of said support at a distance away from the web, the axis of its pivotal mounting and the axis of the pivot pin connecting the first member and bolt lying in a plane substantially at right angles to the plane of said web, said member having spaced apart sides and said sides having curved slots therein through which the pivot pin connecting the bolt and the first member passes, the slots being so located that when the member is disposed substantially at right angles to the connected bolt and first member said pivot pin is in the inner ends of the slots and held against movement away from the web, and manually operable means for moving said second member to release said pivot pin, substantially as described.

LLOYD L. ANDERSON.
